UNITED STATES PATENT OFFICE.

JOSEPH S. WYLIE, OF OKLAHOMA, OKLAHOMA.

HOISTING MECHANISM.

1,210,748.

Specification of Letters Patent. Patented Jan. 2, 1917.

Application filed March 14, 1916. Serial No. 84,129.

To all whom it may concern:

Be it known that I, JOSEPH S. WYLIE, a citizen of the United States, residing at Oklahoma city, in the county of Oklahoma and State of Oklahoma, have invented certain new and useful Improvements in Hoisting Mechanisms, of which the following is a specification.

This invention relates to hoisting apparatus and has for its object the simplification of the supporting structure.

In apparatus heretofore provided, so far as I am aware, the supporting tower or frame work was of expensive construction which required considerable time to build.

It is the object of my invention to provide a support consisting of a single column or mast which will carry the guides for the hoisting bucket or cage and will also support the hopper or platform into or onto which the material is discharged and the chute leading from the said hopper to the point of use, the guides being disposed at one side of the mast or column.

The invention is illustrated in the accompanying drawings and resides in certain novel features which will be hereinafter first fully described and then more particularly pointed out in the claims following the description.

In the drawings: Figure 1 is an elevation of an apparatus for hoisting and distributing mixed concrete embodying my improvements; Fig. 2 is a detail perspective view of the hoisting bucket and the frame in which the same is mounted; Fig. 3 is a detail perspective view of the hopper and a portion of the chute for conveying the concrete from the said hopper; Fig. 4 is a horizontal sectional view showing a modification.

In carrying out my invention, I employ a supporting frame which consists of a mast constructed of corner posts 1 connected by braces 2 and struts 3, as illustrated in the accompanying drawings. At the upper and lower ends of this mast, I provide laterally extended beams 4 and 5 and to the said beams I firmly secure the opposite ends of cables 6 which are stretched taut between the said beams so as to provide vertical guides upon which the hoisting cage may travel.

In the upper beam is mounted a guide pulley 7 over which the hoisting cable 8 passes and a similar guide pulley 9 is provided at the upper end of the mast, the cable passing from the said pulley 9 down through the mast to a similar pulley 10, at the lower end thereof, 60 and thence to the engine.

The hoisting cage or frame 11 is secured to the end of the cable 8 and is carried thereby. In the present instance, this frame is illustrated as constructed of an inverted U-shaped bar having grooves 12 in its side members and having a rod 13 secured in and extending between the lower ends of said members. The guides 6, which may be steel cables or stout rods, fit within the grooves 12 so as to guide the hoisting cage or frame in its vertical movement and prevent the same from swinging away from the mast or out of its operative relation to the hopper. The bucket 14 is mounted upon the rod 13 by loops or eyes 15 which encircle the said rod loosely and thereby constitute a hinge connection with the same. As shown most clearly in Fig. 2, the bucket is extended to one side of the vertical plane of the frame 11 so that it will be overbalanced when loaded and upon operation of the tripping means, which I will presently describe, will automatically swing upon the hinge rod 13 as a center and discharge its contents into the hopper. To hold the bucket normally against a discharging movement, I pivotally mount upon one side of the frame 11 a latch 16 which has one end turned down, as shown at 17, to engage between lugs 18 on the side of the bucket. The opposite end of the latch extends into the path of a trip 19, secured upon the hopper 20 and when the bucket reaches the upper limit of its movement, the free end of the latch will impinge against the said trip so that the latch will be swung about its pivotal point and the downturned end thereof will be withdrawn from between the lugs 18, thereby releasing the bucket so that it will be free to swing and will turn over and discharge its contents into the hopper. The latch is held normally in engagement with the lugs 18 by a spring 21 attached to the latch between its pivot and the lugs and also attached to the adjacent side 105

member of the frame 11, as shown most clearly in Fig. 2.

The hopper 20 may be of any preferred form but should have an inclined bottom 5 leading into the chute or spout 22 which is carried around the mast to lead into a conveyor or chute 23 which may be constructed in any convenient manner so as to extend to the point where the concrete is to be used. 10 The hopper 20 may be supported from the mast in any convenient manner and is provided on its side, adjacent the guide 6, with a shield or plate 24 upon which the bucket will ride in its downward movement so as to be returned to its initial position with the latch 16 in engagement with the lugs 18. 15 The accompanying drawings show the hopper carried by a frame 40 having a sliding engagement with the mast and suspended 20 on cables 41.

In Fig. 4 I have illustrated a different embodiment of the invention, in which the mast is indicated by the numeral 25. To the side of the mast I secure an I-beam 26 and 25 to the outer side or flanged portion of the said I-beam, I rigidly secure a guide plate or rail 27 having its side edges projected beyond the edges of the I-beam. To one side of the hoisting cage or frame, indicated by the reference numeral 28, I secure a guide plate 29 having its edges doubled upon themselves so as to provide U-shaped flanges 30 adapted to fit around the edges of the cleat or plate 27 and thereby hold the 35 cage in a true vertical plane during its movements.

The concrete is mixed in the usual manner and loaded into the bucket 14, after which the engine is operated to raise the bucket 40 and the frame 11 to the hopper 20. As the upper end of the bucket reaches the plane of the upper end of the hopper, the free end of the latch 16 will impinge against the under side of the trip 19 so that continued 45 upward movement of the hoisting cage will cause the said latch to swing upon its pivot and be released from the lugs 18, as will be readily understood and as has been previously stated. The latch will be held in its 50 approximately vertical released position until the hoisting frame or cage descends below the plane of the trip. As soon as the latch is released, the weight of the load in the overbalanced bucket will cause the said bucket to swing over upon the hopper and discharge the concrete into the same, whence it will gravitate through the chutes to the point of use. After the load has been discharged, the bucket and the hoisting frame 55 are permitted to descend and the downward movement of the cage will cause the bucket to ride over the edge of the hopper and be thereby swung back to its initial position, the shield or plate 24 serving to pre-

vent dipping of the bucket until the latch 65 has cleared the trip 19 and been thereupon drawn into engagement with the lugs 18 by the springs 21.

It will be readily noted that I have provided an exceedingly simple apparatus for 70 guiding the bucket in its vertical movements and have produced an apparatus which can be built at a cost appreciably below that of the apparatus now generally employed.

It will be noted that the hoisting cable 75 or bucket is not housed within a complicated and costly tower which practically surrounds or incloses the bucket and forbids access to the same in the event it should for any reason become clogged in the course 80 of its travel either upwardly or downwardly. The bucket is open and accessible at all times so that the loading of the mechanism is facilitated and any concrete which may tend to lodge upon the latching mechanism 85 or other parts, so as to interfere with the proper operation of the same, can be easily reached and removed.

It will be noted that the hopper is mounted on a side of the mast intersecting the 90 side at which the guides are disposed and that the hopper projects laterally from its point of support substantially parallel with the plane of the guides so that the hopper and the bucket are both free or spaced from 95 the mast throughout their operative portions and are, consequently, very easy of access in the event that repairs or other attention should be necessary. This arrangement also provides a very compact structure and facilitates the erection and dismantling of the apparatus. This apparatus 100 is intended more particularly for use in handling concrete during building operations and it is very desirable to have a 105 structure which will firmly support the hopper and the bucket but will be composed of the fewest possible parts so that the apparatus may be quickly and economically erected and also easily, quickly and economically 110 dismantled when the building operation is over. The space required to accommodate the apparatus is also minimized so that the mast and the parts mounted thereon may be accommodated in a corner or a space of 115 small dimensions without in any way decreasing the efficiency of the apparatus or the quantity of material that may be successfully handled therein.

While the invention is intended more particularly for application to apparatus for 120 hoisting mixed concrete and is so illustrated, it will be understood, of course, that the improvements may be used in other fields.

Having thus described the invention, what 125 is claimed as new is:

In an apparatus for the purpose set forth, the combination of a mast, a lateral exten-

sion projecting from one side of the mast, spaced vertical guides carried by said extension and extending the full height of the mast in spaced relation thereto, a hopper supported on a side of the mast intersecting the side from which the lateral extension projects, said hopper extending laterally from the mast and past said guides parallel with the side of the mast on which it is supported, a bucket slidably fitted to 10 said guides, and means for raising and lowering the bucket to and from the hopper.

5 In testimony whereof I affix my signature.

JOSEPH S. WYLIE. [L.S.]
